UNITED STATES PATENT OFFICE.

ALBERT CALDWELL JACKSON, OF DAYTON, OHIO.

COIN-WRAPPING DEVICE.

1,130,978.

Specification of Letters Patent.

Patented Mar. 9, 1915.

Application filed March 9, 1912. Serial No. 682,772.

To all whom it may concern:

Be it known that I, ALBERT CALDWELL JACKSON, a citizen of the United States, residing at Dayton, in the county of Montgomery and State of Ohio, have invented 5 certain new and useful Improvements in Coin-Wrapping Devices, of which the following is a specification.

My invention relates to counting room 10 appliances and particularly to means to facilitate the wrapping of stacks of coins into packages or rouleaux.

The object of the invention is to simplify 15 the structure as well as the means and mode of operation of such devices, whereby they will not only be cheapened in construction, but will be more efficient in use, enabling the wrapping operation to be performed easily, quickly and neatly, and unlikely to 20 get out of repair.

A further object of the invention is to provide such coin wrapping device which will be universal in its application requiring no adjustment of parts to accommodate 25 it to coins of different diameter and in which the coins will be automatically supported in the proper position while leaving them free to rotate.

A further object is to provide a device of 30 such character capable of use for advertising purposes.

With the above primary and other incidental objects in view as will more fully appear in the specification, the invention 35 consists of the features of construction, the parts and combinations thereof, and the mode of operation, or their equivalents, as hereinafter described and set forth in the claims.

40 Referring to the drawings, Figure 1 is a perspective view of the coin wrapping device forming the subject matter hereof, showing the device as constructed of sheet material and with the coins and wrapper in place preparatory to the wrapping operation. Fig. 2 is a longitudinal sectional view of the device shown in Fig. 1. Fig. 3 is an end elevation thereof. Fig. 4 is a perspective view of a modification of the device as 45 constructed of glass, porcelain or other similar material. Fig. 5 is a diagrammatic end view of the device illustrating its universal application to coins of different diameter.

55 Like parts are indicated by similar characters of reference throughout the several views.

The device forming the subject matter hereof comprises a substantially V shaped trough like member arranged at an inclination to the horizontal and having an inward 60 projecting finger or overhanging stud at its lower extremity forming a rest or stop for the collection of coins. In constructing the device there is employed a substantially M shaped body *a* which may be stamped or 65 pressed from sheet material. The V shaped groove *a*¹ of the body *a* is arranged at an inclination to the horizontal as clearly shown in Fig. 2. Secured to the divergent side of the V shaped groove *a*¹ and at the lowermost 70 end thereof is a T shaped stop member *b*, the stem *b*¹ of which projects inward in parallel relation with the V shaped groove and is preferably bent upward at its extremity as shown at *b*² to form a stop or 75 rest for the collection of coins which are to be placed within the V shaped groove *a*¹. In the drawing the stop member *b* has been shown as formed independent of the main body *a* and secured thereto by rivets *b*³. It 80 is obvious however, that this finger or stop might comprise a tongue or finger pressed from the sheet of material forming the main body *a* and so be formed integral therewith. In forming the package or rouleau, the 85 wrapper *c* is first laid across the V shaped groove *a*¹ of the member *a* after which the collection of coins *c*¹ are placed within the groove *a*¹ and upon the wrapper *c*. The collection of coins will be firmly held in contact with the stop or rest *b*² by gravity due to the inclination of the V shaped groove *a*¹. The edge of the wrapper *c* will project beneath the stop or rest *b* and beyond the extremity of the collection of coins as shown 90 in Figs. 1 and 2, thereby providing a projecting end to be folded down to secure the coins after they have been wrapped. 95

By turning the forward edge of the wrapper over the collection of coins as is shown 100 in Fig. 3, placing the fingers thereon and pushing forward, the collection of coins will be rotated within the V shaped groove as is indicated by the dart in Fig. 3 causing the wrapper *c* to be neatly and quickly wrapped thereabout. During this wrapping operation the coins will be held in contact and parallel with each other through their tendency to slide down the V shaped groove under the influence of gravity which sliding movement 105 is prevented by the stop or rest *b*. After the collection of coins have been wrapped as

described, the projecting ends of the wrap-
per are folded down to close the package or
rouleau in the usual manner.

The device may be formed from sheet
5 metal or other material as before mentioned,
or it may be formed from plastic material as
shown in Fig. 4, in which case a stud *d* may
be substituted for the stop *b* before de-
scribed. In the form shown in Fig. 4, the
10 device may be employed not only for wrap-
ping coins but is also useful as a paper
weight. In either of the forms shown in
Fig. 1 or that shown in Fig. 4, the de-
vice is especially adapted for use as an
15 advertising device having peculiar qual-
ifications for displaying bank advertising.
Suitable advertising matter may be dis-
played either on the exterior sides of the
member *a* or upon the divergent side of the
20 V shaped groove thereof as clearly shown in
Fig. 4. Either of these positions afford
broad flat surfaces conveniently located
within the view of the operator.

I am aware that coin wrapping devices
25 have been heretofore employed, but as usu-
ally constructed, such devices embody spring
operated plungers, adjustable stops, or vari-
able gages for maintaining the coins in
proper position during the wrapping opera-
30 tion and such constructions have usually
necessitated a series of devices to accommo-
date coins of different sizes and diameters.

The present device has been designed to
obviate the difficulties heretofore experienced
35 by providing a device which will be uni-
versal in application to coins of all sizes and
which will be devoid of movable or adjust-
able bars, being always in condition to use
with coins of any diameter.

40 From the above description it will be ap-
parent that there is thus produced a coin
wrapper of the character described, possess-
ing the particular features of advantages

before enumerated as desirable, but which
obviously is susceptible of modification in 45
its form, proportion, detail construction and
arrangement of parts, without departing
from the principle involved or sacrificing
any of its advantages.

While in order to comply with the statute, 50
the invention has been herein described in
language more or less specific as to struc-
tural features, it is to be understood that the
invention is not limited to any specific de-
tails, but that the means and mechanism 55
herein described comprise but one mode of
putting the invention into effect, and the in-
vention is therefor claimed broadly in any
of its possible forms or modifications within
the scope of the appended claims. 60

Having thus described my invention, I
claim:

1. As an article of manufacture, a coin
wrapping device comprising in combination,
a body having an unobstructed open inclined 65
V-shaped groove, a bridge member at the
lowermost end of the groove and a stop fin-
ger projection from said member along the
axis of the groove and separated therefrom.

2. As an article of manufacture, a coin 70
wrapping device comprising in combination,
a body having an unobstructed substantially
open inclined V-shaped groove, a bridge
member at the lowermost end of the groove,
a stop finger projecting from said member 75
arranged to stop a plurality of coins a dis-
tance from said member and arranged to
pass one end of a sheet of paper between
the stop finger and groove to the end of said
groove. 80

In testimony whereof, I have hereunto set
my hand this 5th day of March 1912.

ALBERT CALDWELL JACKSON.
